ATTORNEY

UNITED STATES PATENT OFFICE.

SAMUEL C. HOEY, OF WILKINSBURG, PENNSYLVANIA, ASSIGNOR TO WESTINGHOUSE ELECTRIC & MANUFACTURING COMPANY, A CORPORATION OF PENNSYLVANIA.

OIL-CUP COVER.

Application filed November 11, 1919. Serial No. 337,171.

To all whom it may concern:

Be it known that I, SAMUEL C. HOEY, a citizen of the United States, and a resident of Wilkinsburg, in the county of Allegheny and State of Pennsylvania, have invented a new and useful Improvement in Oil-Cup Covers, of which the following is a specification.

My invention relates to oil-cup covers and similar devices, and it has for its object to provide a novel device of the character designated that shall be simple and inexpensive to manufacture and strong and durable in construction.

15 In the accompanying drawing, Fig. 1 is a side view, partially in section and partially in elevation, of a portion of a machine structure provided with a cover constructed in accordance with my invention, and Fig. 2 20 is a plan view of the cover shown in Fig. 1.

Heretofore, oil-cup covers have been made of single pieces of metal attached to the machines for which they were intended, being generally formed of cast metal, and 25 have not readily lent themselves to adaptation for machines of different types.

30 My invention is adapted for use on any machine or mechanism where it is desired to provide an opening for the purpose of inserting oil, waste or other materials or to obtain a view of the interior workings of the machine.

A base member is formed, preferably by stamping, so as to fit closely over the portion 35 of the machine having the opening which it is desired to cover, this base member having an opening therethrough surrounded by an upwardly struck flange. A cover, also 40 preferably formed of pressed metal, is fitted over said last-mentioned opening and is preferably provided with a peripheral flange extending down over the flange on the base member, thus providing a tight closure. The cover member is pivotally mounted on the 45 base member and a spring is associated with the pivot in order to maintain the cover member tightly closed, under normal conditions.

For a more detailed understanding of my 50 invention, reference may now be had to the drawing wherein a machine 1 only a portion of which is shown, is provided with a base member 2 which has an opening 3 therethrough that is surrounded by a flange 4, the member being attached to the machine 1 by

means of screws 5. A cover 6, formed of pressed metal or other suitable material, is provided with a flange 7, fitting over the flange 4 of the member 2 when the cover is closed. An extension 8 of the cover serves 60 as a means for raising it. A pin 9 connects the cover 6 to the base member 2 by means of the flanges of both members. A spring 10 is positioned on the pin 7 and causes the cover 6 to close and stay closed 65 unless subjected to outward pressure. The raised position of the cover is indicated by broken lines in Fig. 1.

Although I have shown the base member 2 so formed as to be tightly seated on a 70 machine portion having a cylindrical contour, it may obviously be shaped to conform to any desired portion of a machine, irrespective of its contour, provided that the difference between the radii of the contact 75 surfaces of the machine element 1 and the base member 2 is not too great. The base member 2 has its greatest rigidity near the flange 4 and its greatest flexibility at its outer edges, wherefore the flexibility of the 80 base member 2 may be increased by increasing the distances between the flange 4 and the outer edges of the base member 2.

Furthermore, although I have shown the member 2 attached to the machine by 85 screws, it may be attached in various other ways, as by being clamped around a portion of the machine.

It will be obvious to those skilled in the art that my invention is susceptible of additional changes and modifications without departing from the spirit thereof and may be used for a great variety of purposes other than those I have mentioned. Therefore, I desire that only such limitations shall be 90 placed thereupon, as are imposed by the prior art or are specifically set forth in the appended claims.

I claim as my invention:—

1. The combination with a flexible base 100 member having an opening therein bounded by an upstanding substantially annular flange, a pin positioned in said upstanding flange, and a cover pivotally mounted upon said pin, of resilient means for maintaining 105 the cover in a closed position.

2. The combination with a flexible arcuate base member having an opening therein bounded by an upstanding substantially 110 annular flange, a pin positioned in said

- member, and a cover pivotally mounted upon said pin, of resilient means mounted upon said pivot pin for maintaining said cover in a closed position.
5. 3. In an oil cup, the combination with a slightly flexible base member having an opening therein and provided with a relatively narrow upstanding substantially annular flange portion around said opening,
- 10 10 a pin positioned in said flange portion, and a cover having flange portions and pivotally mounted upon said pin, of a spring mounted upon said pivot pin for maintaining said cover in a closed position.
- 15 15 4. The combination with a machine element having a curved surface and having an opening therein, of a base member adapted to materially change its curvature to conform to the surface of said
- 20 20 element and having an opening there-

through provided with an exterior upstanding flange therearound, and a cover member pivoted upon said exterior flange and adapted to conform thereto and to tightly close the opening in said base member.

5. The combination with a machine element provided with an opening therein, of a composite closure for said opening embodying a flexible base member fixedly attached to said element and surrounding said opening having an opening therein bounded by an exterior upstanding substantially annular flange portion and a cover-member pivoted upon said flange portion and adapted to close the opening in said base member.

In testimony whereof, I have hereunto subscribed my name this 1st day of Nov., 1919.

SAMUEL C. HOEY.
